ARTICLE

Philip H. Sagarin, Bridgeport, Conn., assignor to Valve
Corporation of America, Bridgeport, Conn., a corpo-
ration of Connecticut

Filed Dec. 27, 1961, Ser. No. 68,081

Term of patent 14 years

(Cl. D58—26)

FIGURE 1 is a front elevational view of a combined closure and dispenser for a pressure packed can or similar article embodying my new design, the broken-line representation of a can being shown for illustrative purposes only.

FIGURE 2 is a side elevational view of the same, the opposite side being substantially a mirror image thereof.

FIGURE 3 is a rear elevational view of the same.

FIGURE 4 is a top plan view of the combined closure and dispenser for a pressure packed can or similar article.

FIGURE 5 is a bottom plan view of the combined closure and dispenser for a pressure packed can or similar article, and

FIG. 6 is an axial sectional view thereof.

I claim:

The ornamental design for a combined closure and dispenser for a pressure packed can or similar article, as shown and described.
